UNITED STATES PATENT OFFICE.

WILLIAM B. HOTCHKISS, OF NEW YORK, N. Y.

DESIGN FOR BANK-BILLS.

Specification forming part of Design No. 7,184, dated February 17, 1874; application filed December 16, 1873.
[Term of Patent 7 years]

To all whom it may concern:

Be it known that I, WILLIAM B. HOTCHKISS, of the city and State of New York, have invented or produced a Design for a Bank-Bill, of which the following is a description:

The accompanying photolithograph illustrates said design.

It is usual in bank-bills to employ a parallelogram having sharp angles or corners; these are objectionable in appearance. My design is made for rendering the bill more artistic and handsome in appearance.

The shape and configuration of the said bank-bill are represented in the drawing. The bill is oblong, and the opposite sides parallel, or nearly so, in the middle portions; but, in-

stead of the corners usual in bank-bills, there is a curve at *b*, uniting the straight bottom and top lines or edges with the ends.

The bank-bill of the aforesaid shape and configuration is much more ornamental and handsome in appearance than those before made.

I claim as my invention—

The design of the shape and configuration of the bank-bill, as described and represented.

Signed by me this 5th day of December, A. D. 1873.

WM. B. HOTCHKISS.
